UNITED STATES PATENT OFFICE.

RICHARD WENSLEY, JR., OF DENVER, COLORADO.

DRUM-TRAP.

No. 839,240.

Specification of Letters Patent.

Patented Dec. 25, 1906.

Application filed February 17, 1906. Serial No. 301,534.

To all whom it may concern:

Be it known that I, RICHARD WENSLEY, Jr., a citizen of the United States, residing in the city and county of Denver and State of Colorado, have invented certain new and useful Improvements in Drum-Traps; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in drum-traps for plumbers' use, my object being to provide a fluid-tight joint between the cap and the body of the trap and at the same time protect the threads of the trap from the 20 corrosive action of its gaseous contents.

This invention belongs to the class of trap in which a screw cap or closure is employed, and the invention is applicable to other constructions adapted to perform a similar function.

25 My further object is to provide a construction of this class adapted to obviate the necessity of a separate packing-washer.

In my improved construction I employ a 30 metal ring screw-threaded interiorly and having an interiorly-projecting ledge at the bottom of the screw-threaded portion. The top of the body of the trap is bent inwardly and made to overlap the ledge. The cap or closure is provided with an exteriorly-threaded 35 depending flange adapted to engage the interior threads of the ring of the trap. The lower edge of the cap is provided with a circular knife-edge adapted to indent the soft metal of the top of the trap, which metal is 40 supported by the ledge of the ring. The body of the trap is ordinarily composed of lead, which is sufficiently soft to allow the sharp edge of the flange of the cap or closure 45 to indent the same between the chamber of the trap and the screw-threads of the cap and ring.

Having briefly outlined my improved construction, I will proceed to describe the same 50 in detail, reference being made to the accompanying drawings.

In the drawings, Figure 1 is an elevation of a drum-trap equipped with my improvements. Fig. 2 is a vertical section of the same. Fig. 3 is a top plan view of the trap. Fig. 4 is a fragmentary sectional view of a

trap provided with my improved construction, with the parts shown on a larger scale.

The same reference characters indicate the same parts in all the views.

Let the numeral 5 designate the body of the trap, which, as heretofore indicated, it will be assumed, is composed of lead or similar soft metal. The ring 6, which is preferably composed of brass, is provided with an 65 interiorly-projecting flange or ledge 7. This ring above the flange is interiorly threaded, as shown at 8, to engage exterior threads of a depending flange 9, formed on the cap or closure 10.

In order to connect the body of the trap with the ring 6, the upper extremity of the trap is carried inwardly and caused to engage the rounded bottom part of the flange 7, and is then bent outwardly on top of the 75 flange or ledge 7 and pressed down against the threaded portion of the ring. The lower edge of the depending flange of the cap or closure 10 is provided with a thin edge 12, adapted to indent the portion 13 of the body 80 of the trap which lies above the ledge 7. This part 13 of the body of the trap really forms a packing-washer, the same being integral with the trap's body.

In order to close the trap, it is only necessary to screw the cap 10 into the ring 6 and down against the soft-metal part 13 of the body of the trap. This makes a fluid-tight joint and prevents the contents of the trap from coming in contact with the threads 90 thereof.

Having thus described my invention, what I claim is—

1. A soft-metal trap or similar device comprising a body part and an interiorly-threaded 95 ring provided with a ledge extending interiorly beyond the bottom of its threaded portion, the top of the body of the trap being bent inwardly and carried upwardly through the ring and finally bent outwardly upon the 100 ledge thereof.

2. A structure of the class described, the combination with the body of the trap, of a ring surrounding the upper portion of the body of the trap and having an interiorly-projecting ledge, over which the top of the trap is bent, the ring having a portion extending upwardly above its ledge and interiorly threaded, and a cap or closure having a depending flange exteriorly threaded to engage the ring, the bottom of the flange of the cap being provided with a thin edge adapted 110

to indent the portion of the trap's body which is supported by the ledge of the ring.

3. In a structure of the class described, the combination of the soft-metal body of the

5 trap, a ring of harder metal surrounding the top of the trap and having a ledge over which the upper edge of the body of the trap is bent, the ring being interiorly threaded, and a cap having a depending exteriorly - threaded

10 flange adapted to engage the threads of the

ring, the bottom of the cap's flange being formed into a thin edge adapted to indent a portion of the body of the trap supported by the ledge, for the purpose set forth.

In testimony whereof I affix my signature 15 in presence of two witnesses.

RICHARD WENSLEY, JR.
